(57) **CLAIM**

The ornamental design for a portable gas tank shroud, as shown and described.

DESCRIPTION

FIG. 1 is a perspective view of the shroud;
FIG. 2 is a left side elevational view of the shroud;
FIG. 3 is a right side elevational view of the shroud;
FIG. 4 is a front elevational view of the shroud;
FIG. 5 is a rear elevation view of the shroud;
FIG. 6 is a top plan view of the shroud; and,
FIG. 7 is a bottom plan view of the shroud.
The broken lines in the drawing depict portions of the portable gas tank shroud that form no part of the claimed invention.
